UNITED STATES PATENT OFFICE.

DAVID F. GEIGER, OF MINNEAPOLIS, MINNESOTA, ASSIGNOR OF ONE-THIRD TO
ARTHUR D. COLE, OF MINNEAPOLIS, MINNESOTA.

MEANS FOR OPERATING POWER-TRANSMITTERS.

1,396,954.

Specification of Letters Patent.

Patented Nov. 15, 1921.

Application filed November 20, 1916, Serial No. 132,262. Renewed March 26, 1921. Serial No. 455,985.

To all whom it may concern:

Be it known that I, DAVID F. GEIGER, a citizen of the United States, residing at Minneapolis, in the county of Hennepin and State of Minnesota, have invented a new and useful Improvement in Means for Operating Power-Transmitters, of which the following is a specification.

This invention relates to improvements in means for operating power transmitters for use more particularly, although not exclusively on tractors, wherein the transmission mechanism is of friction type. The primary object of this invention is to provide simple and improved mechanism for causing the power transmission mechanism to easily and quickly effect forward revolution, idle revolution or reverse revolution of the driven member.

20 A further object is to provide means for actuating the operating mechanism whereby a flexible line can by a pulling and release action cause the various movements of the parts desired.

25 To these ends my invention comprises the features of construction and combinations of parts hereinafter described and claimed.

In the accompanying drawings forming part of this specification, Figure 1 is a side elevation of part of a tractor having my invention applied thereto; Fig. 2 is a plan of part of the structure illustrated in Fig. 1; Fig. 3 is a plan of a detail, part of the structure being in section; Fig. 4 is another 35 plan wherein the parts are illustrated in a different position than that shown in Fig. 3; Fig. 5 is a plan of a fragment of my invention, and Fig. 6 is a section of a fragment of my invention.

40 The drawings illustrate one way of constructing my invention. It will however, be understood that the invention is applicable for other uses than that appearing in the drawings and described by the following specification.

45 In the drawings, let A represent the frame or body of a tractor of suitable construction to support the prime mover 2 and transmission and controlling or operating mechanism forming part of my invention. B indicates one of the traction wheels which is journaled upon the shaft 3, the latter being carried by the frame A. The traction wheel B has an internal gear 4, with the teeth 55 of which the teeth of a pinion 5 mesh, said

pinion being carried by a countershaft 6, which is journaled on the frame A. This counter shaft carries a sprocket wheel 7, which is driven by a link belt 8 passing around a sprocket pinion 9, said sprocket pinion being feathered upon a sleeve 10, which is journaled upon the main crank shaft 11 of the prime mover 2. It will be understood that this mechanism may be duplicated on both sides of the machine, one set of mechanism being adapted to transmit power and drive the wheel B, while the other acts in a similar manner in driving another wheel on the opposite side of the machine not illustrated, but a detail description of which can be obtained from my companion application for improvements in tractors, executed by me of even date herewith. It will be observed that the countershaft 6 constitutes a driven member while the main crank shaft 11 is the driving member.

Disposed on the driving member 11 and adapted to be revolved thereby is a power transmitter C having a pair of friction gears 15 and 16 formed with corresponding inner conical faces 17 and 18. The friction gear 15 is rigidly secured to the driving member 11 by a key 19, and is formed with an internal conical clutch surface 20 with which a clutch member 21 is adapted to move into and out of frictional engagement to transmit motion from the driving member 11 to said clutch member. The clutch member is formed as an integral part of the sleeve 10, which is slidably and freely mounted upon the crank shaft. The sprocket pinion 9, which is adapted to assist in conveying motion to wheel B is slidably secured on the sleeve 10 by the feather 22 and the friction gear 16 is rigidly secured to said sleeve by the same feather, the pinion 9 being interposed between the adjacent friction surfaces of the friction gears. A cup member 25 is secured on the outer end of the driving member 11 slidably over a hub portion 26 formed on the friction gear 16 by means of a set bolt 27 and contains a helical expansion spring 28, which being seated in said cup and pressing against a shoulder 29 on the hub 26, tends to slide the sleeve and the gear member 16 inwardly on the driving member with the friction surface of the clutch member 21 into engagement with the conical surface 20 in the friction gear 100

105

110

15. Thus motion is transmitted by the clutch member 21 from the friction gear 15 and driving member to the friction gear 16, unless the friction gear 16 is forced outwardly along the driving member with the clutch member 21 disengaged from the friction gear 15.

The operation of the power transmitter C is controlled by a friction pinion D, said 10 pinion directly coöperating with the power transmitter. Said pinion D is mounted upon a thrust shaft 35, which is slidably supported in a bearing 36, which is carried by the frame A. The friction pinion D has 15 a conical surface 37, which is arranged in outward position of the shaft 35 out of contact with the conical friction surfaces 17 and 18 (see Fig. 2,) respectively of the friction gears 15 and 16. When said shaft is moved 20 inwardly toward the axis of the driving member 11, the friction gear 16 is first engaged and the friction gear 15 secondly engaged by the friction pinion. These three 25 positions of the pinion constitute successively "go ahead," "stationary" and "reverse" positions, to correspondingly effect the revolution of the driven member 6. When the pinion D is in "go ahead" position as illustrated in Fig. 2, the clutch member 30 21 is held in engagement with the friction gear 15 under the tension of the spring 28. In "stationary" position, the pinion D is adapted to hold the driving gear 16 against the tension of the spring 28 with the 35 clutch member 21 disengaged from the friction gear 15 as illustrated in Fig. 3, the pinion being out of contact with gear 15. In "reverse" position, (see Fig. 4,) both 40 friction surfaces 17 and 18 are engaged by the pinion D, and while the clutch 21 is held in disengaging position, motion is transmitted from the friction gear 15 to the friction gear 16 by said pinion in reverse direction and the driving sprocket 9 revolved in 45 an opposite direction.

The thrust movement of the shaft 35 is effected by hand by the driver or operator who may be situated at a distance from the transmitter C by a flexible line 40, or rod, 50 said line being loosely attached to an eye 41 on the upper end of a controlling lever 42. This controlling lever is pivoted near its lower end by a pin 43 supported by a bearing 44 carried by the frame A. The 55 end of the thrust shaft 35 which slides in the bearing 36 is hingedly connected at its outer end with a portion of the lever 42 above said pivot bearing by means of a pivot and slot connection 46. The lower 60 pending portion of the operating lever 42 below the pivot pin 43 is attached to a spring 45, which is anchored on the main frame of the machine, and normally tends to draw the lever 42 and the thrust shaft 35 into "go 65 ahead" position of the vehicle as illustrated

in Figs. 1 and 2. The upper portion of the lever 42 swings in a quadrant E, said quadrant being supported by the frame A, and formed with a notch 47 and a curved shoulder 48. The upper end of the lever 42 70 also carries a keeper 49 which is formed with three radiating arms 50, 51 and 52, the intermediate portion of said keeper being tiltingly mounted upon the lever arm by means of a pivot 53. When the arm 42 is 75 in "stationary" or "intermediate" portion, that is, when the driven member is at rest, the arm 50 on the keeper engages the quadrant in the notch 47 and is adapted to hold the arm 42 against the tension of the spring 80 45 in median position.

The shoulder 48 on the quadrant is located immediately back of the notch 47, and as the lever 42 is swung by pulling on the line 40 from "stationary" toward "reverse" position, (see Fig. 4,) the keeper arm 50 rides over the shoulder 48, and tilts the keeper back into the position shown in Fig. 4, so that when the lever 42 is released, the keeper will escape the notch 47, and allow 90 the lever to return under the force exerted by the spring 45 into "go ahead" position. This action is permitted by sufficient play and freedom between the shoulder 48 and each of the arms 50 and 52. If it is desired however to move the lever 42 from "stationary" to "go ahead" position, that is from the position shown in Fig. 3 to the position shown in Fig. 1, the arm 50 will escape the notch 47, if the arm 42 is 95 reversed immediately after being drawn past "stationary" position and allowed to return without assuming "reverse" position, (see Fig. 5). A spring catch in the form of a slide 55 (see Fig. 6) movable longitudinally 100 on the lever by an antifriction roller 56 sliding in a longitudinal slot 58 and drawn down by a spring 59 is adapted to engage either of the slanting faces 60 on the upper end of the arm 51, of the keeper, so as to 105 hold the keeper in either "forward" or "backward" position. The antifriction roller 56 is adapted to ride over the crown or apex of the slanting faces 60 when sufficient tilting effort is imparted by the shoulder 48 110 against the lower curved surface of the arms 50 and 52. The force of the spring catch automatically urges the keeper with its arm 50 engaging the notch 47 when the lever 42 is first drawn forward, but allows 115 the pawl to tilt while sweeping over the shoulder 48 when the lever 42 is swung toward "reverse" position until the antifriction roller rides over the crown of the slanting faces 60, whereupon it holds the keeper 120 with its arm 50 tilted up above the notch 47, in which position the keeper is held until the lever 42 is released and the arm 52 sweeps over the shoulder 48 after it is too late for the arm 50 to engage said notch. 125 130

Thus the transmission mechanism is controlled to operate in "idle," "go ahead" or "reverse" positions, by the pulling and releasing action of a flexible or rigid line and 5 without holding the line under tension when the parts assume stationary or at rest position.

In accordance with the patent statutes, I have described the principles of operation 10 of my invention, together with the apparatus which I now consider to represent the best embodiment thereof, but I desire to have it understood that the construction shown is only illustrative, and that the invention can 15 be carried out by other means and applied to uses other than those above set forth within the scope of the following claims.

Having described my invention, what I claim as new and desire to protect by Letters Patent is:

1. Apparatus of the class set forth, comprising, in combination, a revolute driving element, a revolute driven element, transmission mechanism interposed between said 25 parts comprising a friction gear couple having one member attached to said driving element and the other slidably and revolute independently of said first member and connected with said driven member to revolve 30 the latter in one direction, a clutch interposed between said driving and driven members, a revolute pinion slidably disposed between and adapted by sliding movement to disconnect said clutch, spread said gear members and transmit reverse motion from one gear member to the other after said clutch 35 has been disconnected, and means for sliding said pinion.

2. Apparatus of the class set forth, comprising, in combination, driving and driven members, a pair of friction gears, one being attached to said driving member to be driven thereby and the other slidably and revolute carried and attached to said driven member, a clutch interposed between said driving and driven members to effect when engaged the revolution of said driven member in one direction, spring pressed means normally urging said sliding gear and the parts 45 of said clutch into a position to effect the engagement of said clutch, a pinion slidably disposed with its driving face adapted to engage the friction face of one of said friction gears, disconnect said clutch and stop 50 the transmission of power from the driving to the driven members and also movable into a position to transmit reverse motion from

the driving to the driven members, and means for moving said pinion into said positions.

3. Apparatus of the class set forth, comprising, in combination, a pair of driving and driven elements, a transmission unit coupled to said driving and driven elements for revolving the same, means movable into plurality of positions for effecting the operation of said transmission elements, one of said positions causing forward revolution of said driven element, intermediate position permitting idle revolution of said driven element and another position causing reverse revolution of said driven element, an operating lever for changing said positions, means for holding said lever in adjusted position and a flexible line adapted to control the 75 operation of said lever.

4. Apparatus of the class set forth, comprising, in combination, a pair of driving and driven elements, a transmission unit coupled to said driving and driven elements for revolving the same, a single pinion movable into a plurality of positions for effecting the operation of said transmission elements, one of said positions causing forward revolution of said driven element, intermediate position permitting idle revolution of said driven element and another position causing reverse revolution of said driven element, and means associated with said pinion for moving the latter into said positions. 90

5. Apparatus of the class set forth, comprising, in combination, revolute driving and driven elements, transmission mechanism interposed between said parts, comprising a pair of friction gears one being fixed on one of said elements and the other gear fixed on the other of said elements, a clutch interposed between said driving and driven members, resilient means urging the parts of said clutch into engagement to transmit 100 revolving motion from said driving to said driven members and a single pinion slidably disposed between said gear adapted in one position to depress one of said gears and release said clutch to permit the idle revolution of said driven member and in fully inserted position to engage both of said gears while said clutch is released and transmit reverse motion from said driving to said 105 driven members.

In testimony whereof, I have signed my name to this specification.

DAVID F. GEIGER.
